UNITED STATES PATENT OFFICE.

WILLIAM COOPER, OF TRAVERSE CITY, MICHIGAN.

GATE.

SPECIFICATION forming part of Letters Patent No. 445,343, dated January 27, 1891.

Application filed September 8, 1890. Serial No. 364,358. (No model.)

To all whom it may concern:

Be it known that I, WILLIAM COOPER, a citizen of the United States of America, residing at Traverse City, in the county of Grand 5 Traverse and State of Michigan, have invented certain new and useful Improvements in Gates, of which the following is a specification, reference being had therein to the accompanying drawings.

My improvement in gates consists in the novel construction, combination, and arrangement of the parts, substantially as hereinafter more fully described, and shown in the accompanying drawings, in which—

Figure 1 is a side elevation of my gate. Fig. 2 is a detail broken perspective view of the same; and Fig. 3 is a similar view, the parts, however, being extended, and the lower or base rail being omitted from the section A.

My improved gate is arranged to permit its lower section to be swung up or elevated and secured above its normal position—that is, farther above the ground either for ingress or egress of animals or to avoid snow and ice 25 and allow its upper section to be moved upward and downward at convenience.

In accomplishing these objects I construct the gate in sections A, B, and C, the lower sec-

tion B being hinged to the lower ends of the vertical or upright pieces of section C and section A for increasing the height of the gate, being adjustable on section C by the metallic guides D and thumb-screws E. The lower section when lowered is retained in place by its own gravity, and when swung up from the ground is secured by means of hook *a* on section B and metallic eye *b* in section C. The gate-section C is secured to a gate-post, as shown, by means of strap-hinges or in any ordinary manner.

Having thus fully described my invention, what I claim is—

A gate comprising three sections, the lowest or bottom section being hinged to the lower ends of the vertical pieces of the middle section and the top section carrying guides sliding on said vertical pieces of the middle section and adjustable thereon by thumb-screws, substantially as and for the purpose set forth.

In testimony whereof I affix my signature in presence of two witnesses.

WILLIAM COOPER.
